HONING TOOL

Frank L. Gillett, Los Angeles, and John S. Morgan, Jr., Inglewood, Calif., assignors, by mesne assignments, to The National Superior Company, Toledo, Ohio, a corporation of Delaware

Application May 22, 1933, Serial No. 672,206

17 Claims. (Cl. 51—184.4)

This invention relates to hones which are employed for finishing cylindrical surfaces to a high degree of accuracy and quality of finish. The particular embodiment of the invention disclosed herein relates to hones which are employed for finishing the bores of deep well pumping barrels, although the same type of hone can be used to equal advantage for honing motor cylinder bores and such other classes of work wherein a substantial honing tool is required for working in a bore of rather limited diameter.

One of the particular objects of this invention relates to a novel means of expanding the honing stones radially by a rotary feeding mechanism.

Another object of this invention contemplates the use of a yieldable means in combination with the rotary feeding mechanism to feed the honing stones radially outward to a desired diameter against an adjustable stop.

This invention has also for its object a provision to render the yieldable feeding mechanism inoperative and maintain the stones in a retracted position.

Another object of this invention relates to the provision of separate flexible driving connections for the hone and the rotary feeding mechanism which have their axes of movement in substantially the same transverse plane.

A further object of this invention resides in the provision of means for indicating to the operator the rate at which the cylinder bore is being enlarged during the honing operation.

Other objects and advantages of this invention will appear in the following description.

Figure 1 is a side elevation of the hone in the expanded position.

Figure 2 is a longitudinal sectional view taken on line 2—2 of Figure 1.

Figure 3 is a fragmentary longitudinal sectional view showing the rotary feeding mechanism in the retrieved position and taken in a plane perpendicular to the section shown in Figure 2.

Figure 4 is an end elevation of the hone looking directly toward the nose end.

Figures 5, 6, 7, 8 and 9 are cross-sectional views taken on lines 5—5, 6—6, 7—7, 8—8, and 9—9 respectively in Figure 2.

Referring to the drawing, 1 indicates a body having a plurality of radially disposed longitudinal slots 2 in which are mounted a like number of stone holders 3. On the outer face of each holder 3 there is cemented or secured in any other desired manner, a honing stone 4 of the

proper grain and hardness most suitable for the class of work and material to be honed. The holders 3 are yieldably retained in the slots 2 by means of annular coiled springs 5 positioned in annular grooves formed in the body 1 and engaging recesses formed at the ends of the holders 3. The holders are restrained from longitudinal movement by pins 6 or any other suitable shoulders that may be provided. The springs 5 tend to yieldably urge the holders to the retrieved or contracted position.

Journalled within the bore 7 formed axially of the body 1, there is a rotary cam shaft 8 having two spaced cam or eccentric portions 9 for each stone holder provided in the body. The two spaced cam portions 9 for each stone holder are in different transverse planes from the planes of the cam portions for the other stone holders in order to provide a hone of comparatively small diameter with substantial proportioned structural elements and also for the purpose of facilitating the manufacture of the tool with the highest degree of accuracy and economy. In a hone having four stones it is necessary to have a cam shaft 8 with four sets of eccentrics, or a total of eight. The four sets of eccentrics 9 have the same relative angular relation to correspond to the angular relation of the slots 2 in the body 1 in order to obtain a precise uniform radial movement of all the stones upon any rotary movement of the cam shaft 8. The radial movement produced by rotation of the cam shaft 8 is transmitted to the stone holders 3 by balls 10 positioned in radial bores formed in the body 1 at the bottom of the slots 2. A threaded plug 11 in the nose portion of the body 1 closes the open end of the bore 7.

Since the cam portions 9 for the respective stone holders 3 are in different transverse planes, the cam shaft 8 can be designed for any desired angular travel independently of the number of stone holders disposed around the body. In the conventional type of hone having n abrasive elements spaced around the body, the angular range of travel for a rotary cam shaft would be limited theoretically to an angle equal to, or less than 360 degrees divided by n ; whereas, in the present invention, the range of cam shaft travel may be any angle greater or less than 360 degrees divided by n ; however, it is preferable to design the cam shaft to obtain the maximum angular travel to effect the greatest degree of precision in the device.

Between the body 1 and the drive shaft 12 there is provided a drive sleeve 13 having a uni-

versal drive connection with the body 1 consisting of trunnion pins 14 engaging an elongated radial hole 15 in the sleeve 13. A feed shaft 17 is axially aligned in the bore 16 of the drive sleeve 13 with the cam shaft 8. The feed shaft and cam shaft are non-rotatively connected by means of a slot and tongue connection at 18 which has its axis of oscillation in substantially the same transverse plane as the axis of the trunnion pins 14.

10 The feed shaft 17 is normally rotated by means of a coiled torsion spring 19 encircling the sleeve 13. One end of the spring 19 is anchored to the sleeve 13 by means of a free end 20 engaging a collar 21 which is adjustably positioned on the sleeve 13 by means of a screw 22 engaging one of a number of circumferentially spaced holes 23 in the drive sleeve 13.

15 The collar 21 is also drilled with a number of holes 24 to facilitate rotation of the collar for "winding-up" the spring 19 to the desired tension by means of a spanner wrench (not shown). The holes 24 have the same angular spacing as the holes 23 in order to enable the operator to know when the screw 22 is aligned with a hole 23 when adjusting the tension of the spring. The live end of the spring 19 is fixed to a crescent or U-shaped collar 25 seated against a shoulder 26 on the drive sleeve 13. An outer barrel 27 is mounted over the drive sleeve 13 and has a limited degree of rotary and translatory motion. The U-collar 25 is non-rotatably positioned with reference to the barrel 27 by means of a key 28 engaging a slot in the collar 25. The key connection 28 permits a sliding movement of the barrel 27 with reference to the collar 25. A transverse pin member 29 positively connects the barrel 27 with the feed shaft 17 so that any movement given to the outer barrel is imparted directly to the feed shaft which actuates the cam shaft 8.

20 The drive sleeve 13 has an L-shaped slot 30 provided in its wall to permit the desired rotary and sliding movement of the pin 29 which is imparted by manually gripping the knurled portion 31 or employing a standard form of spanner wrench to engage the holes 32 for rotating the barrel. The barrel 27 is provided at one end with a helical cam face 33 which forms a straight faced stop shoulder 34. A cam collar 35 is non-rotatably but slidably positioned on the drive sleeve 13 by means of key 36 sliding in a keyway 37 formed in the drive sleeve 13. The collar 35 is adjustably positioned longitudinally of the sleeve 13 by means of a micrometer adjusting nut 38 threaded on the sleeve 13. A spring detent 39 is fixed to the nut 38 with the free end engaging notches in the periphery of the cam collar 35. Axial movement of the nut 38 determines the axial position of the cam face on the collar 35 and consequently the allowable rotary movement of the barrel 27.

25 In referring to directions of rotation the reference position will be considered as looking toward and at the nose end of the hone. To expand the stones the cam shaft is rotated clockwise and consequently the spring 19 is wound to effect a clockwise force on the barrel 27. To retrieve or contract the stones the barrel 27 is rotated counter-clockwise until the pin 29 strikes the end wall of the L-shaped slot 30 in the drive sleeve 13, and to retain the stones in the retrieved position it is only necessary to slide the barrel 27 outwardly away from the hone until the pin 29 hooks into the recess 40 formed by the L-shaped slot. The face of the pin 29 and the slot 40

30 are formed with a slight under-cut in order

to prevent any accidental movement of the barrel 27 from the retrieved position.

When in the retrieved position the hone is inserted into the piece to be honed and the stones are expanded out into engagement with the cylindrical surface to be honed by releasing the barrel 27 from its latched position. Under the force of the spring 19 the stones are urged yieldably outward with the desired pressure against the surface being honed. The honing operation continues until the desired amount of material is removed from the surface and the honed bore brought to the desired size. Ordinarily, the collar 35 is set to operate as a stop so that the operator will not hone the bore oversize. The stop is effected by the cam face 33 on the barrel 27 striking a complementary face formed on the cam collar 35. In order to indicate to the operator the rate at which the hone is enlarging the bore of the work, there is provided along the face of the cam collar 35 a series of uniform graduations which indicate the amount of hone expansion for some given amount of rotation of the barrel 27. A zero marker is indicated on the cam face of the barrel as a reference point. Due to wear of the stones it becomes necessary to frequently correct the adjustments, which operation merely involves rotating the micrometer nut 38 the desired amount to compensate for the wear of the stones.

While we have herein illustrated one preferred embodiment of our invention, it is to be understood that we do not wish to be limited to the particular structure shown in the drawing but that our invention is of the full scope of the appended claims and is obviously subject to further varied modifications without departing from the spirit of our invention.

We claim:

1. A device of the character described comprising in combination, a body having longitudinally extending abrasive elements, means in operative relation with and adapted to expand said abrasive elements, rotatable means having positive operating contact with the first mentioned means for actuating said first mentioned means, axially adjustable means mounted colinearly with the longitudinal axis of the device and co-operating with said rotatable means to form a stop to adjustably limit the maximum diameter to which said abrasive elements can expand.

2. A device of the character described comprising in combination, a body having longitudinally extending abrasive elements, rotary cam means in operative relation with and adapted to expand said abrasive elements, rotatable means for rotating said cam means to expand said abrasive elements, axially adjustable means mounted colinearly with the longitudinal axis of the device and co-operating with said rotatable means to form a stop to adjustably limit the maximum diameter to which said abrasive elements can expand.

3. In a honing tool, the combination of a body portion having longitudinal slots, expandable abrasive elements radially movable in said slots, rotary cam means to expand said elements, a sleeve portion non-rotatably secured to said body portion, rotatable means including a barrel surrounding said sleeve portion to normally urge the rotation of said cam means to move the abrasive elements to the expanded position, a stop collar non-rotatively mounted on said sleeve portion, cam surfaces on the adjacent faces of said barrel and collar co-operating to form

a stop to limit the expansion of said abrasive elements.

4. A honing tool as claimed in claim 3 in which means are provided to axially adjust the position of said stop collar to vary the maximum diameter to which said abrasive elements can expand.

5. A device of the character described, comprising in combination, a body member, abrasive elements mounted upon said member in radially disposed relation thereto, rotary cam means in operative relation with said abrasive elements, actuating means including a barrel operatively connected with a torsion wound spring for normally and yieldably urging the cam means to rotate and move the abrasive elements outwardly, and means to render said actuating means inoperative when the abrasive elements are in the retrieved or contracted position upon a translatory movement being imparted to said barrel.

6. A device of the character described, comprising in combination, a body member, abrasive elements mounted upon said member in radially disposed longitudinal slots, a rotary cam shaft journalled within an axial bore in said body, radial bores forming openings between the axial bore and the longitudinal slots in said body, balls positioned in each of said radial bores and in contact with the cam portions of said cam shaft and the abrasive elements and means to rotate said cam shaft to effect a radial movement of said abrasive elements.

7. A device of the character described, comprising in combination, a body member having an axial bore formed therein, a set of abrasive elements arranged around said member, each element of said set extending longitudinally of the member for a distance defined by two longitudinally spaced transverse planes which are common to all of said elements, a rotary cam shaft journalled within the axial bore, a plurality of longitudinally spaced cams formed on the shaft in operative relation with said abrasive elements, said cams being positioned in non-coincident transverse planes, and means to rotate said cam shaft to effect a radial movement of said abrasive elements.

8. A device of the character described, comprising in combination, a body member, a set of abrasive elements arranged around said member, each element of said set extending longitudinally of the member for a distance defined by two longitudinally spaced transverse planes which are common to all of said elements, rotary cam means including a plurality of longitudinally spaced rotary cams in operative relation with said abrasive elements, said cams being positioned in non-coincident transverse planes, and means to rotate said cam means to effect a radial movement of said abrasive elements.

9. A device of the character described, comprising in combination, a body having longitudinally extending grinding elements, rotary cam means positioned within said body and in operative relation with said grinding elements, a driving sleeve, a universal joint operatively connecting said sleeve to said body, means within said driving sleeve for rotating said rotary cam means, a universal joint between said latter two means having its axis of movement in substantially the same transverse plane with that of the first mentioned universal joint.

10. In a honing tool, the combination of a body portion, abrasive elements carried by the body portion, a sleeve portion non-rotatively secured

to the body portion, means including a rotatable element for expanding said abrasive elements upon rotation being imparted to said rotatable element, means operative throughout the operating range of the abrasive elements to impart rotation to said rotatable element, an axially adjustable indicating stop means including a non-rotatable element mounted axially of the sleeve portion and cooperating with said rotatable element to limit the maximum diameter to which said abrasive elements can expand.

11. In a honing tool, the combination of a body portion having longitudinally extending abrasive elements, means in operative relation with said elements and adapted to expand said elements, a sleeve portion non-rotatably secured to the body portion, rotatable means mounted axially of said sleeve portion and adapted to actuate the first named means upon rotation being imparted to said rotatable means, an elastic power medium to impart rotation to said rotatable means, axially adjustable indicating stop means surrounding the sleeve portion and cooperating with said rotatable means to limit the maximum diameter to which said abrasive elements can expand.

12. In a honing tool, the combination of a body portion having longitudinal slots, expansible abrasive elements movable in said slots, operative means including rotary cam means within the body to expand said elements upon rotation being imparted to said rotary cam means, a sleeve portion non-rotatably secured to said body portion, rotatable means mounted axially of said sleeve portion and operatively connected with the rotary cam means, axially adjustable indicating stop means surrounding the sleeve portion and cooperating with said rotatable means to limit the maximum diameter to which said abrasive elements can expand.

13. In a honing tool, the combination of a body portion, abrasive elements carried by the body portion, a sleeve portion non-rotatively secured to the body portion, means including a rotatable element for expanding said abrasive elements, a barrel mounted on the sleeve portion and operatively connected with the rotatable element, a spring collar rotatably mounted on the sleeve portion and engaging a stop shoulder, a torsion wound spring mounted axially of the sleeve portion and anchored at one end to the sleeve portion and at its other end to the spring collar, means including a relative non-rotatable sliding connection between the spring collar and the barrel whereby the torsion spring normally and yieldably urges the rotatable element to rotate and move the abrasive elements outwardly, and means provided for permitting a translatory movement of said barrel to latch the same in an inoperative position when the abrasive elements are in the retrieved or contracted position.

14. A honing tool as claimed in claim 13, in which an extension is formed on said barrel for enclosing the torsion wound spring.

15. A device of the character described, comprising in combination, a body member, abrasive elements mounted in substantially equally spaced angular relation around said member, rotary cam means in operative relation with said abrasive elements, said cam means having separate rotary cam surfaces for actuating each abrasive element and, means to rotate said rotary cam means, said individual cam surfaces being formed to permit rotation of said cam means through an angle corresponding to the effective angular operating range of the individual cam surfaces

which is greater than 360 degrees divided by the number of angularly spaced abrasive elements.

16. A device of the character described, comprising in combination, a body member, abrasive elements mounted upon said member in radially disposed relation thereto, rotary cam means in operative relation with said abrasive elements, actuating means including a torsion wound spring and a barrel for normally and yieldably urging the cam means to rotate and move the abrasive elements outwardly, an extension formed on said barrel for enclosing the torsion wound spring, and means to render said actuating means inoperative when the abrasive elements are in the retrieved or contracted position upon a translatory movement being imparted to said barrel.
17. In a honing tool, the combination of a body

portion having longitudinal slots, expandible abrasive elements movable in said slots, operative means including rotary cam means to expand said elements upon rotation being imparted to said rotary cam means, a sleeve portion non-rotatably secured to said body portion, rotatable means mounted axially of said sleeve portion and operatively connected with the rotary cam means, an elastic power medium to effect rotation of said rotatable means, axially adjustable indicating stop means surrounding the sleeve portion and cooperating with said rotatable means to limit the maximum diameter to which said abrasive elements can expand. 5
